FLUID PRESSURE BRAKE DEVICE

Filed July 23, 1927

UNITED STATES PATENT OFFICE.

EARLE S. COOK, OF WILMERDING, PENNSYLVANIA, ASSIGNOR TO THE WESTINGHOUSE AIR BRAKE COMPANY, OF WILMERDING, PENNSYLVANIA, A CORPORATION OF PENNSYLVANIA.

FLUID-PRESSURE-BRAKE DEVICE.

Application filed July 23, 1927. Serial No. 207,839.

This invention relates to automatic train control apparatus and more particularly to that type having means for automatically effecting a brake pipe reduction in two stages.

5 In the pending application of Thomas H. Thomas and Earle S. Cook, Serial No. 109,044, filed May 14, 1926, means are disclosed for automatically effecting a split or two stage reduction in brake pipe pressure, whenever the train control apparatus operates to make a brake application on the train.

Whether or not a two stage reduction in brake pipe pressure is required for applying the brakes on a train is mainly dependent upon the train speed. If the train speed is low, the retarding force on the train, caused by applying the brakes, develops much more rapidly than if the train speed is high, so that as a result, when the train speed is high, 20 the brakes may be applied by effecting a single and full reduction in brake pipe pressure, without causing any damage to the train.

The principal object of my invention is to provide means for automatically causing a 25 two stage reduction in brake pipe pressure to be effected below a predetermined speed limit and for causing a continuous brake pipe reduction to be effected above a predetermined speed limit.

30 In the accompanying drawing, the single figure is a diagrammatic view of a train control apparatus embodying my invention.

As shown in the drawing, the apparatus may comprise a governor valve unit, a brake 35 valve device 1, and a split reduction valve device 2.

The construction and operation of the governor valve unit of this application is substantially the same as that of the construction 40 disclosed in the Patent No. 1,553,603 of Clyde C. Farmer, granted September 15, 1925, while the construction and operation of the brake valve device 1 and split reduction valve device 2 is substantially the same 45 as that of the construction disclosed in the pending application of Thomas H. Thomas and Earle S. Cook, Serial No. 109,044, filed May 14, 1926, and these devices therefore will not be described in detail, but only to the extent deemed necessary to a full and complete 50 understanding of the invention.

The governor valve unit comprises a governor portion 3, a change speed valve portion 4, a timing portion 5, and a magnet portion 6.

The governor portion 3 comprises a governor 55 7 of the usual centrifugal type, adapted to be rotated according to the speed of the train and in operation is adapted to cause movement of a crosshead member 8, carrying a plurality of adjustable tappet stems, 60 adapted to operate corresponding valves at various train speeds, said valves comprising governor speed valves 9, 10 and 11 and blow down timing valves 12 and 13.

The change speed valve portion 4 comprises a casing containing a high speed valve device and a medium speed valve device. The high speed valve device comprises a piston 14, contained in a chamber 15 and a slide valve 16 contained in a chamber 17 and 70 adapted to be operated by said piston. The medium speed valve device comprises a piston 18, contained in a chamber 19 and a slide valve 20 contained in the chamber 17, and adapted to be operated by the piston 18. 75

The timing portion 5 comprises a casing containing a high to medium speed timing valve device and a medium to low speed timing valve device. The high to medium speed timing valve device comprises a diaphragm 21, subject on one side to the fluid pressure in a chamber 22 and on the opposite side to the pressure of a coil spring 23, the diaphragm 21 being adapted to operate a double beat valve 24, contained in a valve chamber 25. The medium to low speed timing valve device comprises a diaphragm 26, subject on one side to the fluid pressure in a chamber 27 and on the opposite side to the pressure of a coil spring 28, the diaphragm 26 being adapted to operate a valve 29 contained in a spring and valve chamber 30 and a valve 31 contained in a spring and valve chamber 32. 80 85 90

The magnet portion 6 comprises a high speed magnet valve device 33 and a medium speed magnet valve device 34. The high speed magnet valve device 33 comprises a magnet and valves 35 and 36 operable by said magnet. The medium speed magnet valve 95 device 34 comprises a magnet and valves 37 and 38 operable by said magnet.

The brake valve device 1 comprises rotary valves 39 and 40, contained in a chamber 41 and adapted to be operated by a handle 42, 100 and the usual equalizing piston mechanism, which comprises an equalizing piston 43, forming a chamber 44 at one side and a cham-

ber 45 at the opposite side, said piston being adapted to operate a brake pipe discharge valve 46. Said brake valve further comprises a cut-off valve 47, contained in a chamber 48, and carried by a stem secured to a piston 49, contained in a piston and spring chamber 50. Associated with the brake valve device is a brake application valve portion, which may comprise a piston 51, contained in a chamber 52 and a slide valve 53 contained in a chamber 54 and adapted to be operated by said piston. A spring 55, contained in chamber 52, opposes outward movement of said piston.

15 The split reduction valve device 2 comprises a control valve portion and a hold-back portion. The control valve portion comprises a piston 56, contained in a chamber 57 and a piston 58 contained in a chamber 59. Said pistons have different areas, are connected by a stem, and are adapted to operate a slide valve 60 contained in a chamber 61, formed intermediate said pistons. The hold-back portion comprises a piston 62, contained in a chamber 63 and a slide valve 64, contained in a chamber 65 and adapted to be operated by said piston. Inward movement of the piston 62 is opposed by a spring 66.

30 In operation, fluid under pressure is supplied from a main reservoir 67 to the rotary valve chamber 41 of the brake valve device 1 and to the feed valve devices 68 and 69 through a pipe and passage 70. Fluid at the usual pressure carried in the brake pipe is supplied by the feed valve device 68 to the seat of the rotary valve 40 through pipe and passage 98, and with the brake valve device in running position, as shown in the drawing, said fluid flows from passage 98 through port 72 in the rotary valve 40 and passage 73 to the cut-off valve chamber 48 and to the seat of the application slide valve 53.

45 Fluid at the pressure employed in the operation of the train control apparatus is supplied by the feed valve device 69 to the application valve chamber 54, to the seat of the control slide valve 60 of the split reduction valve device, to the speed valve chamber 17 and the timing valve chamber 32 of the governor unit and to the magnet valve chambers 74 and 75, through pipe and passage 76 and from said passage 76 in the governor unit through a choked passage 77 and a passage and pipe 78 to the application piston chamber 52. Fluid under pressure also flows to said piston chamber 52 through a port 79 in the application piston 51. The fluid pressure thus equalizes on the opposite sides of the application piston 51 so that said piston and slide valve 53 are held in the release position, as shown in the drawing, by the pressure of spring 55, in which position, cavity 133 in the slide valve connects passage 73 to passage 81 leading to the cut-off piston cham-

ber 50, so that fluid at feed valve pressure is permitted to flow from passage 73 to the piston chamber 50 and act on the cut-off piston 49 to open the cut-off valve 47 and permit fluid under pressure to flow to the brake pipe 82 and to the equalizing piston chamber 45 by way of passage 83. Fluid at feed valve pressure is also supplied from the feed valve device 68 to the equalizing piston chamber 44 and to the equalizing reservoir 115 through passage 78, cavity 84 in the application slide valve 53 and passage 85, so that the fluid pressure becomes equal on the opposite sides of the equalizing piston 43 and ensures seating of the discharge valve 46.

70 In territory governed by a high speed signal indication, the magnet of the high speed magnet valve device 33 is energized and the magnet of the medium speed magnet valve device 34 is deenergized. With the high speed magnet energized, the valve 35 is seated and the valve 36 is unseated, which permits fluid under pressure to flow from the valve chamber 75 to the high speed piston chamber 15, wherein it equalizes with the fluid pressure in the valve chamber 17, and the pressure of a spring 86 then holds the high speed piston 14 and slide valve 16 in the inner position, in which, fluid is permitted to flow from the valve chamber 17 through port 87 in the slide valve and passage 88 to a blow down reservoir 89 and to the diaphragm chamber 27 of the timing valve portion 5. The pressure in chamber 27 acts on the diaphragm 26 to seat the valve 29 and unseat the valve 31. With the valve 31 unseated, fluid under pressure flows from the valve chamber 32 to the medium speed piston chamber 19 by way of passage 90, and equalizes therein with the pressure of the fluid in the valve chamber 17, and the pressure of a spring 91 then holds the medium speed piston 18 and slide valve 20 in the high speed position, as shown in the drawing. With the medium speed slide valve 20 in the high speed position, a timing reservoir 92 is vented to the atmosphere through pipe 93, through a ball check valve device 94, through pipe and passage 95, through a port 96 in the medium speed slide valve 20, and through the atmospheric exhaust passage 97.

100 With the high speed slide valve 16 in the inner position, fluid is supplied to the diaphragm chamber 22 of the timing valve portion 5 and to the high to medium blow down reservoir 124 by way of passage 123.

105 With the brake pipe discharge valve 46 seated, the control piston chamber 57 of the split reduction valve device is vented to the atmosphere through passage and pipe 99, and the exhaust choke plug 100 in the brake valve device. Brake pipe pressure in the control piston chamber 59, acting on the piston 58, then holds the control pistons 56 and 58 and

slide valve 60 in the normal position as shown in the drawing, in which position, the hold-back piston chamber 63 is vented to the atmosphere through passage 101, cavity 102 in the control slide valve 60 and the atmospheric exhaust passage 134. Since the timing reservoir 92 is connected with passage 101 through pipe and passage 103, through the choked passage 104 and past the ball check valve 105, said reservoir is also normally at atmospheric pressure.

With the hold-back piston chamber 63 vented to the atmosphere, the pressure of spring 66 holds the hold-back piston 62 and slide valve 64 in the outer position, in which, a cavity 106 connects passages 107 and 108 leading to a first and a second reduction reservoir 109 and 110, respectively. Both of said reduction reservoirs are normally vented to the atmosphere, the first reduction reservoir through pipe and passage 107, cavity 111 in the application slide valve 53, and the atmospheric exhaust passage 112 and the second reduction reservoir through pipe and passage 108, cavity 113 in the rotary valve 39 of the brake valve device and the atmospheric exhaust passage 114.

When a train is running above a medium speed limit, as in territory governed by a high speed signal indication, the high speed governor valve 11 is seated and both the medium speed and low speed governor valves 10 and 9 are unseated, while both of the blow down valves 12 and 13 are held in their open position.

If the speed of a train exceeds a predetermined high speed limit the high speed governor valve 11 is unseated by operation of the governor 7 and thereby vents the application piston chamber 52 to the atmosphere through pipe and passage 78 and said unseated valve. The fluid pressure in the application valve chamber 54 then shifts the application piston 51 and slide valve 53 to the outward or application position, in which, cavity 111 in slide valve 53 connects passage 81 from the cut-off piston chamber 50 to the atmosphere, through the exhaust passage 112, thereby venting the fluid from said chamber and permitting the opposing pressure of the brake pipe fluid to shift the cut-off piston 49 outwardly and close the cut-off valve 47, so as to prevent further flow of fluid to the brake pipe 82. In application position of the application slide valve 53, cavity 84, therein, connects passage 85 from the equalizing reservoir 115 and equalizing piston chamber 44 to passage 107 leading to the first reduction reservoir 109, so that the fluid under pressure from the equalizing reservoir 115 and piston chamber 44 is permitted to flow to the first reduction reservoir and cause a predetermined decrease in the fluid pressure acting in chamber 44 upon the equalizing piston 43. Said equalizing piston then op-

erates the discharge valve 46 in the well known manner to cause a corresponding decrease in the pressure of the fluid in the brake pipe.

The fluid discharged from the brake pipe 70 past the valve 46 and into passage 99 is partially vented to the atmosphere through the choke plug 100. Said choke plug has less capacity than the opening past the unseated discharge valve 46, so that a pressure is built 75 up in passage and pipe 99 and the control piston chamber 57, which pressure, acting on the control piston 56, shifts said piston and the piston 58 and slide valve 60 to a downward position, in which, cavity 102 connects 80 passage 76 from the feed valve device 69 to passage 101 leading to the hold-back piston chamber 63. Fluid at the pressure supplied by the feed valve device 69 then flows to the hold-back piston chamber and acts to shift 85 the hold-back piston 62 and slide valve 64 to the inward position, in which the cavity 106 disconnects the passages 107 and 108 leading to the first and second reduction reservoirs. Fluid at feed valve pressure from 90 passage 101 also flows through the choked passage 104 and passage 103 to the timing reservoir 92.

With the train in territory governed by a high speed signal indication, the medium 95 speed piston 18 and slide valve 20 are maintained in their inner position, as hereinbefore described, so that the fluid under pressure supplied to the timing reservoir 92 flows to the atmosphere through the port 96 in the 100 medium speed slide valve 20 and the atmospheric exhaust passage 97. Since the capacity of the choked passage 104 in the split reduction device is less than the capacity of the exhaust from the timing reservoir 92, the 105 timing reservoir is thereby maintained substantially at atmospheric pressure.

When the brake pipe pressure is reduced a degree corresponding substantially to the degree of first reduction in equalizing reservoir 110 pressure, the brake pipe discharge valve 46 starts to close and throttle the flow of fluid under pressure from the brake pipe into the passage and pipe 99. When the rate of discharge past the discharge 115 valve 46 thus becomes less than the venting capacity of the choke plug 100, the pressure in the control piston chamber 57 starts to reduce and when reduced to a predetermined degree, the pressure of the brake 120 pipe fluid in piston chamber 59 shifts the control pistons 56 and 58 and slide valve 60 to their upper position, in which, the hold-back piston chamber 63 is connected to the atmosphere through passage 101, cavity 102 125 in the control slide valve 60 and the atmospheric exhaust passage 134. The pressure in the hold-back piston chamber 63 is thereby reduced almost instantly, so that the hold-back piston 62 and slide valve 64 are shifted 130

to their outer position by the pressure of spring 66, in which position, the second reduction reservoir 110 is connected to the first reduction reservoir 109, and the fluid under pressure 5 from the equalizing reservoir 115 and first reduction reservoir 109 is permitted to flow to the second reduction reservoir and effect a second reduction in equalizing reservoir pressure. The equalizing piston 43 then operates 10 the discharge valve 46 to cause a further reduction in the pressure of the brake pipe fluid. It will be noted that the discharge valve 46 does not fully close in order to permit the split reduction device to initiate the 15 second reduction in equalizing reservoir pressure, so that as a result, the brake pipe reduction, caused by both the first and second reductions in equalizing reservoir pressure, is a continuous reduction.

20 During the second reduction, the hold-back piston 62 and slide valve 64 of the split reduction device are prevented from operating to again separate the two reduction reservoirs and thereby interfere with the second 25 reduction, on account of the control pistons and slide valve being held in their upper position by the pressure of fluid from a lock-up reservoir 116, which fluid is permitted to flow to the valve chamber 61 through passage 118 30 and port 117 in the control slide valve 60, said lock-up reservoir becoming charged while effecting the first reduction, by fluid under pressure from the brake pipe, which fluid flows thereto through the passage 83 in 35 the brake valve device 1, cavity 119 in the application slide valve 53, passage and pipe 120, cavity 121 in the control slide valve 60 of the split reduction device and passage 118.

If it is desired to limit the degree of the 40 second reduction in equalizing reservoir pressure to that required for effecting a full service application of the brakes, the brake valve device must be moved to lap position, in which position, the atmospheric connection 45 of the second reduction reservoir, through the exhaust passage 114 in the brake valve device, is cut off. Under this condition, the degree of reduction is limited to the equalization of the fluid under pressure from the 50 equalizing reservoir into the first and second reduction reservoirs.

If a train is running in high speed territory and the signal indication changes to a medium speed, the magnet of the high speed magnet valve device 33 becomes deenergized and the magnet of the medium speed magnet valve device 34 becomes energized. Deenergization of the high speed magnet permits valve 36 to seat and valve 35 to unseat, said latter 55 valve thereby permitting the fluid under pressure in the high speed piston chamber 15 to be vented to the atmosphere. The pressure of the fluid in the valve chamber 17 then shifts 60 the high speed piston 14 and slide valve 16 to the outward position, in which, cavity 122

in said slide valve connects passage 123 from the high to medium blow down reservoir 124 and the diaphragm chamber 22 of the timing portion 5 to passage 125 leading to the opened blow down valve 12. When the fluid pressure acting on the diaphragm 21 is thereby reduced a predetermined degree, the pressure of spring 23 deflects said diaphragm downwardly, thereby permitting the double beat valve 24 to seat in the downward position and thus connect passage 78 from the application piston chamber 52 to the chamber containing the medium speed governor valve 9, which is unseated above the medium speed limit. The application piston chamber 52 is thereby vented to the atmosphere and an automatic application of the brakes is initiated in the same manner as hereinbefore described.

In medium speed position of the high speed slide valve 16, cavity 126 therein connects 85 passage 88 from the diaphragm chamber 27 of the timing portion 5 and from the medium to low blow down reservoir 89 to passage 127 leading to the chamber 128 in the medium speed magnet valve device 34. Since in 90 medium speed territory the magnet of said device is energized, the valve 37 is seated and the valve 38 is unseated, which permits the flow of fluid under pressure from the valve chamber 74 to the diaphragm chamber 27 and the blow down reservoir 89, thereby maintaining the pressure on the diaphragm 26, so as to hold the valve 29 seated and the valve 31 unseated, said latter valve permitting the fluid pressure to be maintained in the medium speed piston chamber 19. Thus, the medium speed territory the medium speed piston 18 and slide valve 20 are maintained in their inner position, in which, the atmospheric connection of the timing reservoir 92 is maintained, which results in causing a continuous brake pipe reduction to be effected in the same manner as hereinbefore described.

If a train is running in medium speed territory and the signal indication changes to a low speed, the magnet of the medium speed magnet valve device becomes deenergized and the high speed magnet remains deenergized. Deenergization of the medium speed magnet permits valve 38 to seat and valve 37 to unseat, said latter valve thereby permitting the fluid under pressure from the diaphragm chamber 27 of the timing portion 5 and from the medium to low blow down reservoir 89 to be vented to the atmosphere past the open 110 blow down valve 13. When the pressure acting on the diaphragm 26 is thus reduced a predetermined degree, the pressure of spring 28 deflects the diaphragm 26, thereby permitting valve 31 to seat and valve 29 115 to unseat, said latter valve thereby permitting the fluid under pressure to be vented from the medium speed piston chamber 19 to the atmosphere, by way of passage 90 and past said unseated valve. The fluid pressure 120

in valve chamber 17 then shifts the medium speed piston 18 and slide valve 20 to the outer position, in which, cavity 129 connects passage 78 from the application piston chamber 52 to passage 130 leading to the chamber containing the low speed governor valve 10, which is open above the low speed limit. The fluid under pressure in the application piston chamber 52 is thereby vented to the atmosphere to initiate an application of the brakes in the manner hereinbefore described.

In the outward position of the medium speed slide valve 20, passage 95 from the timing reservoir 92 is connected through cavity 131 to passage 80, which latter passage leads to the chamber containing the medium speed governor valve 9 and to the top of the ball check valve 132 in the timing portion 5. Below the medium speed limit, the governor valve 9 is seated, so that when the split reduction valve device 2 operates to supply fluid to the timing reservoir 92, the fluid from said reservoir flows only to the governor valve 9 and the ball check valve 132 and, as a result, a pressure is built up in the timing reservoir equal to the pressure in the hold-back piston chamber 63. When the first reduction in brake pipe pressure is completed and the hold-back piston chamber 63 is connected to the atmosphere through the passage 134, a period of time is required to reduce the pressure in the hold-back piston chamber 63 to that at which the spring 66 shifts the hold-back piston 62 and slide valve 64 to the outward position, since the fluid from the timing reservoir 92 flows back to said piston chamber and must also be reduced. Therefore, a period of time elapses from the end of the first reduction in brake pipe pressure to the outward movement of the hold-back piston 62 and slide valve 64 and the consequent starting of the second reduction in equalizing reservoir pressure, so that the brake pipe pressure is therefore reduced in two separate stages with a time interval elapsing between said two stages.

If a train is operating in territory governed by a high speed signal indication and the indication changes to low speed, the medium speed piston 18 and slide valve 20 are shifted to the outward position, as just described above, but in this case, if the train speed is above a medium speed limit, the equalizing reservoir pressure is reduced in the same manner as when a brake application is effected by a change from a high speed to a medium speed signal indication, as hereinbefore described, because, above the medium speed limit the medium speed governor valve 9 is unseated, which provides an atmospheric vent from the timing reservoir 92 and hold-back piston chamber 63, thereby permitting the split reduction valve device to effect a continuous reduction in equalizing reservoir pressure. If, however, the train

speed is below the medium speed limit and a change from a high to a low signal indication occurs, a split or two stage reduction is effected, since below the medium speed limit the governor valve 9 is seated, so that the fluid supplied to the timing reservoir 92, by operation of the split reduction device during the first reduction, is not vented to the atmosphere, but instead a pressure is built up in said timing reservoir to govern the time elapsing between the end of the first reduction in brake pipe pressure and the start of the second reduction in said pressure, in the same manner as hereinbefore described.

The ball check valve device 94 is adapted to prevent the flow of fluid under pressure from the governor unit to the timing reservoir 92. When an automatic application of the brakes occurs in territory governed by a medium speed signal indication and the medium speed piston 18 and slide valve 20 are moved to the outward position, the cavity 131 in said valve connects passage 80, leading to the ball check valve 132, to the passage 95 leading to the timing reservoir 92, so that there would be a tendency for the fluid supplied to the application piston chamber 52 of the brake valve device through port 79 in said piston, to flow through pipe and passage 78, past the double beat valve 24, seated in its lower position, past the ball check valve 132, through passage 80 to passage 95, and from thence to the timing reservoir 72. This would tend to maintain the pressure in the timing reservoir 92 and the hold-back piston chamber 63 of the split reduction device and prevent the movement of the hold-back piston 62 and slide valve 64 to the outer position, as shown in the drawing, so as to start the second reduction in equalizing reservoir pressure. Introducing the ball check valve device 94 between the pipes 93 and 95 prevents the flow of fluid under pressure from passage 78 to the split reduction device and thereby prevents such undesired action.

Having now described my invention, what I claim as new and desire to secure by Letters Patent, is:—

1. In a train control apparatus, the combination with a brake pipe, of means for effecting a reduction in brake pipe pressure in two stages comprising a timing reservoir, a valve device subject to the pressure of fluid in said reservoir and operative to initiate the second reduction in brake pipe pressure, and a valve device operable according to the signal indication for controlling the pressure of fluid in said reservoir.

2. In a train control apparatus, the combination with a brake pipe, of means for effecting a reduction in brake pipe pressure in two stages comprising a timing reservoir, a valve device subject to the pressure of fluid in said reservoir and operative to initiate

the second reduction in brake pipe pressure, a speed controlled valve, a valve device having one position for connecting said reservoir to the atmosphere and another position 5 for connecting said reservoir to said speed controlled valve, and signal controlled means for controlling the operation of said valve device.

3. In a train control apparatus, the combination with a brake pipe, of means for effecting a reduction in brake pipe pressure in two stages comprising a timing reservoir, a valve device subject to the pressure of fluid in said reservoir and operative to initiate the 10 second reduction in brake pipe pressure, valve means having a position in which said reservoir is connected to the atmosphere, and signal controlled means operated under a high speed signal indication for maintaining said valve device in said position.

4. In a train speed control apparatus, the combination with a brake pipe, of means for effecting a reduction in brake pipe pressure in two stages comprising a timing reservoir, 15

a valve device operated upon an increase and 25 then a decrease in pressure in said reservoir for initiating the second reduction in brake pipe pressure, and means operated when the train is permitted to run at high speed for preventing an increase in pressure in said 30 reservoir.

5. In a train control apparatus, the combination with a brake pipe, of means for effecting a reduction in brake pipe pressure, a timing reservoir, a source of fluid under 35 pressure, means operated during the period the brake pipe pressure is reducing for supplying fluid from said source to said reservoir, a valve device operated upon a predetermined reduction in pressure in said reservoir for effecting a second reduction in 40 brake pipe pressure, and means controlled according to the signal indication for preventing a substantial increase in pressure 45 in said reservoir by flow from said source.

In testimony whereof I have hereunto set my hand.

EARLE S. COOK.
